UNITED STATES PATENT OFFICE.

FRANK ZALESKI, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,338,348.

Specification of Letters Patent. Patented Apr. 27, 1920.

Original application filed December 8, 1917, Serial No. 206,215. Divided and this application filed May 13, 1918. Serial No. 234,047.

To all whom it may concern:

Be it known that I, FRANK ZALESKI, a subject of the Emperor of Germany, residing at Boston, county of Suffolk, State of Massachusetts, have invented an Improvement in Sewing-Machines, of which the following description, in connection with the accompanying drawing, is a specification, like characters on the drawing representing

10 like parts.

This invention relates to sewing machines of that type which are provided with upper-thread-handling mechanism and under-thread-handling mechanism and are adapted 15 to perform a predetermined stitching operation and then to be automatically brought to rest. As an example of sewing machines of this type I would refer to buttonhole sewing machines that are adapted when set in 20 operation to form the overseam stitches on a buttonhole and then to be brought to rest automatically at the completion of the buttonhole. Some sewing machines of this type 25 are provided with means for cutting the under thread beneath the work at the end of the stitching operation; and the present invention relates particularly to a sewing machine of this type.

The upper-thread-handling mechanism 30 usually comprises an eye-pointed needle by which the upper thread is manipulated, and the under-thread-handling mechanism includes a looper arranged to take the loops of upper thread as they are inserted through 35 the work by the upper needle and an under needle for inserting loops of under thread through the loops of upper thread.

Sewing machines of this type are usually 40 constructed and arranged so that when they are brought to rest at the end of each seam or stitching operation, the upper needle is in raised position and the upper thread from the upper needle extends through the work and around the looper of the under-thread-handling mechanism. Hence on the under 45 side of the work there will be found not only the under thread leading from the work to the source of supply, but also the loop of upper thread which extends from the work 50 under the looper and back through the work again to the upper needle.

If a sewing machine of this type is provided with thread-trimming mechanism for trimming the under thread close to the work

at the end of the stitching operation, such 55 thread-trimming mechanism will operate to cut not only the under thread, but also the loop of upper thread which is held by the looper. This cutting of the loop of upper thread will produce a short length of thread 60 which is apt to drop into the under-thread-handling mechanism, and after the machine has been in operation for a considerable time there will be quite an accumulation of such thread ends which are apt to clog up or interfere with the operations of the under-thread-handling mechanism.

The object of the present invention is to provide a construction by which the production of these thread ends will be prevented 70 and I accomplish this herein by means which becomes operative during the forming of the last stitch to prevent the looper from engaging the loop of upper thread so that when the sewing machine is brought to rest 75 with the needle raised there will be no loop of upper thread held by the looper and the thread-trimming mechanism, therefore, will operate only on the under thread.

In order to give an understanding of my 80 invention, I have illustrated in the drawings a selected embodiment thereof which will now be described, after which the novel features will be pointed out in the appended claims.

85 In the drawings, Figure 1 is a side view of a sewing machine embodying my invention;

Fig. 2 is a plan view of the driving and stopping mechanism therefor;

Fig. 3 is a plan view of the work-holding means;

Fig. 4 is a fragmentary view showing the thread-trimming device;

Fig. 5 is a view of the under-thread-handling mechanism;

Fig. 6 is a top plan view of the under-thread-handling mechanism;

Fig. 7 is a fragmentary view showing the normal operation of the looper;

100 Figs. 8 and 9 are views showing the operation of the looper during the last stitch-forming movement;

Fig. 10 is a section on the line 10-10, 105 Fig. 1.

I have chosen to illustrate my invention herein as it would be applied to a button-hole sewing machine of the well-known

Reece type, an example of which may be found in United States Letters Patent No. 1,188,942, dated June 27, 1916. This sewing machine comprises work-holding means by which the work is held and stitch-forming mechanism for producing the button-hole stitches. The work-holding means is in the form of a clamp plate 1 which is slidably mounted upon the bed plate 2 of the sewing machine frame and work clamps 3 carried by arms 4 pivoted to the clamp plate and which are movable toward and from the clamp plate for clamping the work *w* and releasing it.

15 The stitch-forming mechanism comprises upper thread-handling mechanism in the form of an eye-pointed needle 5 carried by the needle bar 6 which is mounted for vertical reciprocation in the head or overhanging arm 7 of the frame, and an under-thread-handling mechanism which is mounted on a rotary turret 8 and which comprises an under or lower oscillating needle 9 and a looper 10. The turret 8 is mounted for rotation in suitable bearings 11 carried by the depending portion 12 of the frame, and it is provided at its upper end with a throat-plate 13 having an opening 99 through which the upper and under needles operate.

20 25 The required movements of the under needle 9 and looper 10 are secured from a spindle 20 which is mounted in the turret for vertical reciprocation.

The looper 10 is secured to a block 79 pivoted at 91 to the turret 8, said block having a cam slot 78 therein in which operates a roll 77 carried by the spindle 20. The vertical movements of the spindle thus operate through the cam slot to oscillate the 40 block 79 and the looper 10. The spindle is connected at its lower end to a rocking lever 21 pivotally mounted at 22, the rear end of said lever having a link 23 connected thereto which is actuated from an eccentric 45 on the driving shaft 24 of the stitch-forming mechanism.

The turret has a pinion 14 rigid therewith which meshes with a segmental gear 15 carried by a rock-shaft 16, and the needle bar 50 6 also has a pinion 17 thereon which meshes with a segmental gear 18 carried by the rock-shaft 16. The rock-shaft 16 is operated at the proper time from a main cam 19 so as to turn the turret and upper needle 55 during the stitching around the ends of the buttonhole. The work-holding means and the stitch-forming mechanism are arranged to have a movement relative to each other, and in the machine herein shown, this 60 movement is provided for by making the work-holding means capable of reciprocating movement on the bed plate, such reciprocating movement being derived from the feed cam 19 by any suitable means

usually employed in buttonhole machines of this type.

25 indicates a buttonhole cutter pivotally mounted to the frame at 26 and which is actuated from the cam 19 at the proper time to cut the buttonhole.

I have above referred briefly to some of the essential parts of a buttonhole sewing machine of the type above mentioned, and before entering into a description of my improvements, I will recite briefly the sequence 75 of operations performed in stitching a buttonhole.

When the machine is at rest, the needle 5 and work clamp 3 are both raised and the work-holding means is so positioned that the work *w* supported thereby will be placed properly to have the buttonhole cut therein by the cutter 25, this being referred to as the buttonhole-cutting position. When the machine is started, the work clamps 3 are 80 first depressed against the work *w* to clamp the latter to the clamp plate 1, and the cutter 25 is actuated to cut the buttonhole. As soon as the buttonhole is cut, the clamp plate is given a quick movement toward the 85 left in Fig. 1 to bring the work into buttonhole-stitching position, at which time the shaft 24 is set in operation to actuate the stitch-forming mechanism to cause it to produce a series of stitch-forming movements 90 which form the edge stitches on the cut buttonhole. During the stitching operation the work-holding means is given a slow feeding movement first in one direction and then in the other to cause the stitches to be 95 formed down one side of the buttonhole and then back along the other side, the stitch-forming mechanism being rotated at the ends of the buttonhole so that the 100 stitches will be properly formed around the 105 buttonhole end. When the stitching on the buttonhole is completed, the shaft 24 is brought to rest automatically by a suitable stop motion, the work clamps 3 are raised, and the work-holding means is given a quick 110 movement to the right, Fig. 1, to bring it from stitching to buttonhole-cutting position again, at which time the machine comes to rest.

The shaft 24 is driven from a driving belt, 115 and said shaft is started in operation or brought to rest by shifting the belt either onto the pulley 39 which is fast on the shaft, or onto the pulley 40 which is loose on the shaft. The shifting of the belt is accomplished by a belt shifter 41 carried by a belt-shifting rod 42. When the belt is shifted onto the loose pulley 40, the machine is brought to rest with the needle raised by means of a stop motion which is herein 120 shown as comprising a stop cam 43 fast on the shaft 24, and a stop member 44 which is yieldingly carried by an arm 45 fast on the

actuator rod 42. When the machine is to be started the actuator rod is moved to carry the belt onto the fast pulley 39, in which position it will become locked, and this movement will carry the stop member 44 laterally out of engagement with the stop cam 43. At the end of the stitching operation the actuator 42 is released automatically and the spring 46 will force it longitudinally to shift the belt onto the loose pulley. This will bring the stop member 44 in the path of the stop cam 43. The engagement of the eccentric portion of the stop cam with the stop member 44 will produce a braking effect, and when the stop cam has been turned into the position shown in Fig. 1, so that the notch 47 therein comes in line with the end 48 of the member 44, said end will drop into the notch thereby positively stopping the shaft 24.

The machine herein shown is provided with means for seizing and gripping the under thread at the end of the stitching operation and also means for severing the under thread between the holding means and the work. The means for seizing and holding the under thread is similar to that illustrated and described in my co-pending application, Se. No. 206,215 filed December 8, 1917, of which the present application is a division, and is in the form of a curved arm 27 fast on a rock-shaft 29 mounted in bearings in a bracket 30 carried by the turret, said arm having a hook 28 at the end thereof. The arm 27 is normally held in the position shown in Fig. 6 and the rock-shaft 29 has an arm 32 thereon situated to be engaged by a lever or arm 33 pivoted at 34 to the frame and acted upon by a spring 35 which normally holds it against the stop 37.

In the operation of the machine after the stitch-forming mechanism has been brought to rest and while the work is being carried from stitching to buttonhole-cutting position the turret is turning clockwise, Fig. 6, during which movement the arm 32 will engage the arm or lever 33, and as the arm 32 is wiping past the arm 33, the hook 27 will be swung to the left Fig. 6. When the arm 32 passes off from the arm 33, the hook will be returned to the position shown in Fig. 6. During this swinging movement of the hook 28 it engages the under thread and draws the latter to one side against the under face of the throat-plate 13. The machine herein shown is also provided with means for cutting the under thread close to the work after it has been clamped to the throat-plate 13. Such thread-cutting mechanism is similar to that illustrated and described in my above-mentioned co-pending application Se. No. 206,215, filed December 8, 1917, and comprises two levers 51, 52 pivotally mounted on two studs 53

and 54, respectively, that are carried by a plate 55 which is removably secured to the clamp plate 1 by means of screws 56. The lever 51 carries at its end a cutting block 57 and the lever 52 carries at its end a knife 530, said knife and cutting block operating in close proximity to the upper face of the clamp plate 1. The opposite ends of the levers are connected by a spring 54 which tends to separate the operative ends 75 from each other. Situated between the levers is a toggle device comprising two toggle members 58, 59 pivotally connected at 60 and each of which has rocking engagement with one of the levers, as shown 80 at 61. When the toggle device is broken the cutter 530 and cutting block 57 will be separated from each other but the straightening of the toggle lever will bring the knife into engagement with the cutting 85 block. Means are provided for thus straightening the toggle lever after the stitching operation is completed and while the work is being carried from stitching to buttonhole-cutting position. Such means 90 comprises a lever 63 pivoted at 64 to the plate 55 and connected at one end to the stud 60 of the toggle device, the other end 66 of the lever projecting beyond the clamp plate and operating in a recess 67 formed 95 in the controlling member 68 that is carried by the bed-plate 2 of the machine. The recess 67 is so positioned and of such dimensions that during the movement of the clamp plate 1 from stitching to buttonhole- 100 cutting position, the end 66 of the lever will be brought against the shoulder 69 of the recess thereby turning the lever and straightening the toggle device. The under thread will thus be cut close to the work 105 during the movement of the clamp plate from stitching to buttonhole-cutting position.

In the ordinary operation of a sewing machine of this type the upper needle carries 110 a loop of upper thread *t* through the work and through a loop of under thread at each penetrating thrust and the looper 10 is actuated to engage each loop of upper thread after it has been carried through 115 the work and through the loop of under thread, the looper retaining said loop of upper thread open while the under needle is retracted and is again moved forwardly to carry a loop of under thread through 120 such open loop of upper thread. The looper maintains its engagement with the loop of upper thread while the needle 5 is raised. Hence when a sewing machine of 125 this type is brought to rest with the needle 5 raised, a loop of under thread will be held by the looper 10 and if the thread is cut beneath the work by threat-cutting mechanism, such as above described, a short length of thread will be produced which 130

constitutes the loop of upper thread. One such short length will result from each buttonhole and after the machine has been in operation for sometime the accumulation 5 of these short lengths is apt to clog up and interfere with the operation of the under thread mechanism.

It is the object of my present invention to provide means for preventing the looper 10 from engaging the loop of upper thread during the last stitch-forming movement, so that when the machine is brought to rest there will be no loop of upper thread held by the looper. Consequently, the operation 15 of cutting the under thread will not be accompanied by the formation of any short length resulting from cutting the loop of upper thread.

I accomplish this object by retarding 20 the motion of the looper during the last stitch-forming movement so as to cause it to miss or skip the loop of upper thread.

It will be remembered that the motion of the looper is derived from the vertical 25 movement of the spindle 20, the latter having a roll 77 which operates in a cam slot 78 formed in a member 79 that is connected to the looper, and that during the stitching operation the vertical reciprocations of the 30 spindle 20 occur at such intervals as to cause the looper to properly enter each loop of upper thread. This operation is illustrated diagrammatically in Fig. 7 wherein the needle 5 is illustrated as being withdrawn 35 from the work, thus to throw out the loop *t* of upper thread and the point of the looper 10 is illustrated as just entering the loop *t*.

To cause the looper to miss the loop during the last stitch-forming movement, the 40 movement of the spindle 20 is retarded so that the forward movement of the looper will not occur until after the needle 5 has been raised to such a point as to lift the loop *t* of upper thread above the looper. If, for 45 instance, when the needle is in the position shown in Fig. 7, the looper 10 is retracted to occupy the position shown in Fig. 8, then by the time the looper reaches the point of the needle, the latter will be elevated into 50 the position shown in Fig. 9, in which position the eye of the needle is above the looper and the looper will, therefore, miss the loop *t* of upper thread. I propose to secure this retarding or retracting movement of the 55 looper by means controlled by the stop motion so that just when the machine is coming to rest and the needle 5 is being raised during the last stitch-forming movement, the looper will receive its retarding or re- 60 tracting movement and will thus skip the last stitch. The lever 21 by which the spindle 20 is given its vertical reciprocation is pivotally mounted on a pivotal pin 22 carried by the frame 12. The ends 80 of this 65 pivotal pin which is journaled in the

frame 12 are eccentrically situated, and as a result, if the pivotal pin 22 is turned about its ends 80 as an axis, the lever 21 will be raised or lowered, and since the rear end of the lever is connected to the rod 23, such 70 raising or lowering will be effective at the front end where it is connected to the spindle 20. One of the ends 80 has an arm 81 fast thereon which is connected to the lower end of a rod 82 that extends up through the 75 bed plate and is connected at its upper end to a lever 83 fast on a rock-shaft 84 that is journaled in a bracket 85 carried by the bed plate. Said rock-shaft has an arm 86 fast thereon which is situated in position to be 80 engaged by a finger 87 extending from the stop member 44 when said stop member is being depressed by the eccentric portion of the stop cam. Hence, when the stop motion is set in operation to bring the machine 85 to rest and the stop cam is acting on the stop member 44, the downward swinging movement of the latter will rock the lever 83 thereby raising the rod 82 and turning the pin 22. This will raise the lever 21 and 90 consequently raise the spindle 20 slightly, such movement operating to retract or retard the looper relative to the upper needle. In other words, during the last stitch-forming movement the looper is thrown out of 95 time with the other elements of the stitch-forming mechanism and the looper is thus caused to miss or skip the loop *t* of the upper thread. Hence when the cutter is actuated there will be only the under thread 100 and stay-cord leading from the under side of the work, both of which will be cut close to the work. When the stitching operation is started on the next buttonhole the looper is automatically returned to its normal position in proper timed relation with the upper needle because the starting of the stitching operation involves shifting the actuator rod 42 to carry the belt onto the fast pulley, and this movement of the actuator rod 110 carries the arm 87 laterally out of engagement with the arm 86. The rod 82 is acted upon by a spring 100 which tends to force it downwardly, and, therefore, as soon as the arm 83 has been released from its engagement with the arm 87, the spring 100 will return the looper to its proper position. 115

I have thus provided means operative automatically during the formation of the last stitch to cause the looper to miss or skip the 120 last loop of upper thread, and while I have illustrated herein a selected embodiment of my invention, I do not wish to be limited to the constructional features shown.

The means herein shown for holding and 125 gripping the under thread and for severing it close to the work are not claimed herein as they form the subject matter of my above-mentioned co-pending application Se. No. 206,215, of which this is a division. 130

I claim:

1. In a sewing machine, the combination with work-holding means, of stitch-forming mechanism comprising upper-thread-handling mechanism and under-thread-handling mechanism, means to give said stitch-forming mechanism a series of stitch-forming movements and then bring it to rest, means to prevent the interlocking of the upper and under threads during the last stitch-forming movement, and means to cut the under thread beneath the work at the completion of the stitching operation.
2. In a sewing machine, the combination with work-holding means, of stitch-forming mechanism comprising upper-thread-handling mechanism and under-thread-handling mechanism, the latter having provision for delivering a stay-cord to the work as the stitches are formed, means to give said stitch-forming mechanism a series of stitch-forming movements and then bring it to rest, means to prevent the interlocking of the upper and under threads during the last stitch-forming movements of the series, and means to cut the under thread and stay cord beneath the work at the completion of the stitching operation.
3. In a sewing machine, the combination with work-holding means, of stitch-forming mechanism comprising upper thread-handling mechanism and under-thread-handling mechanism, means to give said stitch-forming mechanism a series of stitch-forming movements and then bring it to rest, means to prevent the interlocking of the upper and under threads during the last stitch-forming movement, and a device on the work-holding means to cut the under thread beneath the work at the completion of the stitching operation.
4. In a sewing machine, the combination with work-holding means including a clamp plate for supporting the work and work clamps to clamp the work thereagainst, of stitch-forming mechanism comprising upper-thread-handling mechanism and under-thread-handling mechanism, means to give said stitch-forming mechanism a series of stitch-forming movements and then bring it to rest, means to prevent the interlocking of the upper and under threads during the last stitch-forming movement of the series, and means carried by the clamp plate to cut the under thread beneath the work.
5. In a sewing machine, the combination with work-holding means including a clamp plate for supporting the work and work clamps to clamp the work thereagainst, of stitch-forming mechanism comprising upper-thread-handling mechanism and under-thread-handling mechanism, the latter having provision for delivering a stay-cord to the work as the stitches are formed, means to give said stitch-forming mechanism a series of stitch-forming movements and then bring it to rest, means to prevent the interlocking of the upper and under threads during the last stitch-forming movement of the series, and means carried by the clamp plate to cut the under thread beneath the work at the end of the stitching operation.
6. In a sewing machine, the combination with work-holding means, of stitch-forming mechanism comprising upper thread-handling mechanism and under-thread-handling mechanism, means to give said stitch-forming mechanism a series of stitch-forming movements and then bring it to rest, means for producing a relative movement between the work-holding means and stitch-forming mechanism both during the stitch-forming movements and after the stitch-forming mechanism has been brought to rest, means to prevent the interlocking of the upper and under threads during the last stitch-forming movement of the series, and means actuated by such relative movement to cut the under thread beneath the work at the end of the stitching operation.
7. In a sewing machine, the combination with work-holding means, of stitch-forming mechanism constructed to concatenate upper and under threads and including loop-engaging means beneath the work for engaging the loops of upper thread, means to give said stitch-forming mechanism a series of stitch-forming movements, means to render the loop-engaging means inoperative during the last stitch-forming movement of the series, and means to cut the under thread beneath the work at the end of the stitching operation.
8. In a sewing machine, the combination with work-holding means, of stitch-forming mechanism constructed to concatenate upper and under threads and including loop-engaging means beneath the work for engaging the loops of upper thread, means to give said stitch-forming mechanism a series of stitch-forming movements, means to render the loop-engaging means inoperative during the last stitch-forming movement of the series, and means carried by the work-holding means to cut the under thread beneath the work at the end of the stitching operation.
9. In a sewing machine, the combination with work-holding means, of stitch-forming mechanism constructed to concatenate loops of upper and under threads and comprising a needle to insert loops of needle thread through the work, and a looper operating beneath the work to take the loops of needle thread as they are inserted through the work, means to give said mechanism a series of stitch-forming movements, and means to retard the action of said looper relative to that of the needle during the last stitching operation.

stitch-forming movement of the series so as to cause it to fail to engage a loop of upper thread.

10. In a sewing machine, the combination with work-holding means, of stitch-forming mechanism constructed to concatenate loops of upper and under threads and comprising a needle to insert loops of needle thread through the work and a looper operating beneath the work to take the loops of needle thread as they are inserted through the work, means to give said mechanism a series of stitch-forming movements, a stop motion to bring the stitch-forming mechanism to rest at the end of the stitch-forming movements, and means actuated by the stop motion to prevent the interlocking of the upper and under threads during the last stitch-forming movement of the series.
- 15 11. In a sewing machine, the combination with work-holding means, of stitch-forming mechanism constructed to concatenate loops of upper and under threads and comprising a needle to insert loops of needle thread through the work and a looper operating beneath the work to take the loops of needle thread as they are inserted through the work, means to give said mechanism a series of stitch-forming movements, a stop motion to bring the stitch-forming mechanism to rest at the end of the stitch-forming movements, and means actuated by said stop motion to retard the action of the looper during the last stitch-forming movement thereby to prevent it from engaging the loop of upper thread.
- 20 12. In a sewing machine, the combination with work-holding means, of stitch-forming mechanism constructed to concatenate loops of upper and under threads, said stitch-forming mechanism including loop-engaging means beneath the work to engage the loops of upper thread, means to give said

mechanism a series of stitch-forming movements, means to retard the action of said loop-engaging means during the last stitch-forming movement of the series so as to cause it to fail to engage the loop of upper thread, and means to cut the under thread beneath the work at the end of the stitching operation.

13. In a sewing machine, the combination with work-holding means, of stitch-forming mechanism comprising upper-thread-handling mechanism and under-thread-handling mechanism, means to give said stitch-forming mechanism a series of stitch-forming movements, a stop motion to bring the stitch-forming mechanism to rest at the end of the stitch-forming movements, and means actuated by the stop motion to prevent the interlocking of the upper and under threads during the last stitch-forming movements of the series, and means to cut the under thread beneath the work at the end of the stitching operation.

14. In a sewing machine, the combination with work-holding means, of stitch-forming mechanism arranged to concatenate loops of upper and under threads and comprising loop-engaging means beneath the work to engage the loops of upper thread, means including a stop motion to give said mechanism a series of stitch-forming movements and then to bring it to rest, means actuated by said stop motion to retard the action of the loop-engaging means during the last stitch-forming movement thereby to prevent it from engaging the loop of upper thread, and means to cut the under thread beneath the work at the end of the stitching operation.

In testimony whereof, I have signed my name to this specification.

FRANK ZALESKI.
